UNITED STATES PATENT OFFICE.

HELEN T. KRACKE, OF BROOKLYN, NEW YORK.

DESIGN FOR AN EMBLEM OR THE LIKE.

Application filed April 6, 1928. Serial No. 26,149. Term of patent 7 years.

To all whom it may concern:

Be it known that I, HELEN T. KRACKE, a citizen of the United States of America, residing in the borough of Brooklyn, county of Kings, city and State of New York, have invented a new, original, and ornamental Design for an Emblem or the Like, of which the following is a specification, reference being had to the accompanying drawing, forming a part thereof.

In the drawing, Fig. 1 is a front view of an emblem illustrating my new design.

Fig. 2 is a side view of the same.

I claim:

The ornamental design for an emblem or the like, substantially as shown.

This specification signed this 27th day of March, 1928.

HELEN T. KRACKE.
